UNITED STATES PATENT OFFICE.

JOSEPH A. STEINMETZ, OF PHILADELPHIA, PENNSYLVANIA.

JOINT-FASTENER.

No 826,125.

Specification of Letters Patent.

Patented July 17, 1906.

Application filed June 24, 1905. Serial No. 266,752.

To all whom it may concern:

Be it known that I, JOSEPH A. STEINMETZ, a citizen of the United States, residing at Philadelphia, in the county of Philadelphia and State of Pennsylvania, have invented 5 certain Improvements in Joint-Fasteners, of which the following is a specification.

This invention is designed to provide simple and inexpensive means for effectively 10 holding together abutting members, such as sections of wood conduits, timber ends, floor-boards, deck-planks, and the like.

In the accompanying drawings, Figure 1 represents a perspective view of the invention, and Fig. 2 represents a sectional view 15 thereof in its operative relation to two abutting members.

The device consists, essentially, of a body 20 of sheet metal having tines struck from the metal thereof and projecting in opposite directions therefrom.

As shown in the drawings, it consists, preferably, of the body portion 1, having the oppositely-extending tines 2 on parallel edges 25 thereof and the oppositely-extending tines 3 projecting from the interior of the body, the tines being struck out of metal forming the body and bent at right angles thereto.

The edge tines are preferably made longer 30 than the body-tines and may be provided with the crimps 2' to stiffen them, so that they

will resist the tendency to bend under transverse stress while being forced into the abutting members 4.

Fasteners of this character can be struck 35 out of sheet metal very readily and without waste of material, providing effective means for joining together abutting wood members of various kinds.

While it is preferred to form the device by 40 striking the same out of sheet metal, it may be formed by casting a body or plate with tines projecting from opposite faces thereof.

Having described my invention, I claim—

1. A joint-fastener comprising a sheet-metal body with tines formed from the metal 45 extending in opposite directions and disposed along and within edges, the edge tines being tapered and extending alternately in opposite directions.

2. A joint-fastener comprising a sheet-metal body with tapered tines formed from the metal, extending in opposite directions, and disposed along and within the edges, the edge tines being crimped and of greater length 55 than the interior tines.

In testimony whereof I have hereunto set my name this 23d day of June, 1905.

JOSEPH A. STEINMETZ.
